CONTAINER FOR KEYS, NOTE PADS, AND
SIMILAR ARTICLESKurt M. Vogel, Fairfield, Conn., assignor to The
Vogel Manufacturing Company, Bridgeport,
Conn., a corporation of Connecticut

Application May 27, 1949, Serial No. 95,700

3 Claims. (Cl. 150—28)

1

The present invention relates to a container for keys, note pad and similar articles, particularly of the type adapted to be carried in the pocket, and has for an object to provide such a container which is relatively flat in form, is free from projecting parts that may cause abrasion or wear in the person's pocket, and which provides an effectual protective enclosure for the articles carried therein.

A further object is to provide a container which may be economically manufactured from plastic material by standard plastic moulding methods, and particularly in which all of the operative parts are included as integral parts of a one-piece moulded structure. It is proposed to construct the container of plastic material having the characteristics of pliability and inherent elasticity, suitable materials for this purpose being, for example, the thermoplastic materials known as Polythene, a Du Pont product, and Polyethylene, a Bakelite product.

A further object is to provide a container including integral catch means for retaining the enclosure in closed position and which is operable into retaining and releasing position through the inherent elasticity of the material of the container.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a plan view of the container, according to one illustrated exemplary embodiment of the invention, the same being shown in flattened position with its inner side exposed, and showing a key holding assembly secured thereto.

Fig. 2 is an end view, as seen from the right in Fig. 1.

Fig. 3 is a lower edge view, as seen from the bottom in Fig. 1.

Fig. 4 is a plan view showing the container in closed position.

Fig. 5 is a lower edge view, as seen from the bottom in Fig. 4.

Fig. 6 is an end view, as seen from the right in Fig. 4.

Fig. 7 is a vertical sectional view, taken along the line 7—7 of Fig. 4.

Fig. 8 is a sectional view, similar to Fig. 7, showing one of the key hooks extended from the container with the container in closed position.

Fig. 9 is a horizontal sectional view, taken

2

along the line 8—8 of Fig. 1, the key holding assembly, as shown in Fig. 1, being removed for the sake of clearness.

Fig. 10 is a horizontal sectional view showing 5 the cover portion of the container being pressed into closed position with respect to the back portion.

Fig. 11 is a horizontal sectional view showing the container in closed position.

10 Fig. 12 is a horizontal sectional view showing the one hand operation of opening the container, the dot-and-dash lines showing the cover portion in open position.

Fig. 13 is a horizontal sectional view showing 15 the container with a note pad attached thereto.

Fig. 14 is a horizontal sectional view showing the container with a ring holder for loose-leaf note sheets attached thereto.

20 Fig. 15 is a vertical sectional view showing the container with a box of cleaning tissues contained therein, one of the cleaning tissues being partially extracted.

Fig. 16 is a vertical sectional view of a modified form of the container, and showing a coin 25 dispenser carried therein.

Fig. 17 is a perspective view showing the container used as a picture carrying and display case.

Referring to the drawings, the container, 30 according to the illustrated exemplary embodiment of the invention, is in the form of a one-piece moulded structure produced by standard plastic moulding methods from plastic material, and particularly a plastic material which in its

35 finished moulded state is pliable and has a high coefficient of inherent elasticity, so that when it is bent or deformed from its normal shape it quickly returns to such normal state. This characteristic is known in the plastic industry as plastic "memory." Suitable materials for this

40 purpose are the thermoplastic materials known as Polythene, a Du Pont product, and Polyethylene, a Bakelite product. These materials have additional characteristics which are especially 45 advantageous for their use in the container of the invention, namely they are highly resistant to wear, are relatively smooth and soft to the touch, are resistant to deterioration by acids and similar agents, and may be readily cleaned with

50 ordinary soap and water.

The container is of generally rectangular form in its flattened open position as shown in Fig. 1, as well as in its folded closed position as shown in Fig. 4, and comprises a rectangular back portion 55 10, a rectangular cover portion 11, corresponding

in outline shape to the back portion, and a foldable hinge portion 12 in the form of a web integrally connected between the inner edges of the back and cover portions, the hinge portion 12 being relatively thinner than the back and cover portions so that it has greater flexibility. This thinness of the hinge portion is obtained by downwardly offsetting its inner surface so that shoulders 14 and 15 are provided at the inner edges of the back and cover portions and convexly curved transversely in the closed position of the container. The outer surfaces of the back and cover portions and the hinge portion are flush.

The back portion 10 is provided along its outer marginal edge with an upstanding side wall 16 and along its upper and lower marginal edges with upstanding end walls 17 and 18 terminating at their inner ends contiguous to the shoulder 14. The cover portion 11 is similarly provided along its outer portion marginal edge with an upstanding side wall 19 and along its upper and lower marginal edges with upstanding end walls 20 and 21 terminating at their inner ends contiguous to the shoulder 15. The side walls 16 and 19 and the lower end walls 18 and 21 are of equal height, and in the closed position of the container the walls 19 and 21 of the cover are disposed in outwardly surrounding relation to the walls 16 and 18 of the back portion, the walls 16 and 18 being spaced inwardly from the edges of the back portion to a greater extent than the inward spacing of the walls 19 and 21 from the edges of the cover portion. The upper end walls 17 and 20, however, are arranged so that in the closed position they abut each other to provide a slit in the upper end of the container. For this purpose the upper end wall 17 and a contiguous portion of the side wall 16 are of relatively reduced height, and the upper end wall 20 is also of relatively reduced height, so that in the closed position the combined height of the walls 17 and 20 is equal to the height of the side and lower end walls. The shoulder 22 at the outer end of the upper end wall 20 is curved into the side wall 19, so that in the closed position, as shown in Fig. 4, this shoulder embraces the corner between the walls 16 and 17 of the back portion, thus presenting an unbroken appearance, as shown in Fig. 6. The purpose of forming the upper end walls 17 and 20 so that they provide a slit along the upper side of the closed container will be presently more fully pointed out.

Substantially centrally of the side wall 16 there is provided upon its outer side a wedge-shaped catch portion 23 formed upon an inwardly offset portion 24 of the wall 16, so that the edge of the catch portion projects beyond the outer surface of the wall and a pocket is provided in the wall beneath the flat under surface of the catch portion. In spaced relation below the catch portion there is provided a finger-engaging stud portion 25, extending from the wall portion 24 slightly beyond the outer edge of the back portion 10, and which is adapted to be engaged by the thumb during the opening operation of the container, as will presently more fully appear.

Centrally of the side wall 19 of the cover portion 11 there is provided upon its inner side a shaped catch portion 26 formed upon an outwardly offset portion 26a of the wall 19, adapted in the closed position of the container to engage beneath the catch portion 23. A groove 27 in the catch portion 26 embraces the stud portion 25 in the closed position of the container.

The operation of closing and opening the container is as follows: As shown in Fig. 9 the container is in its fully open flattened position, this being the form of the container as it is produced in a plastic moulding press. The portion 12 between the back and cover portions constitutes a spring hinge, as well as a closure for one side of the closed container. Its inherent elasticity is such that it exerts a lateral force to maintain the catch means in interengaged relation and also exerts an opening force on the cover when the catch means is released. To close the container the cover and back are simply pressed together, the catch portion 26 of the cover first engaging the inclined surface of the catch portion 23 of the back portion, and engaging beneath the catch portion 23 as the cover shifts forwardly and downwardly as indicated by the arrows in Fig. 10, the connecting spring hinge portion 12 permitting such shifting movement of the cover relatively to the back. As the cover reaches its closed position the inherent elasticity of the hinge portion retracts the cover laterally to the normal closed position as shown in Fig. 11. In the closed position the side and end walls 16 and 18 are fitted within the side and end walls 19 and 21 and constitute a double thickness supporting wall structure between the back and cover portions so that the container has substantial rigidity. The container is adapted to be opened by one hand operation, as shown in Fig. 12, the thumb being engaged with the stud portion 25 and pressed inwardly, causing the back portion to become slightly bowed and disengaging the catch portion 23 from the catch portion 26, the cover automatically swinging to open position as it is released. As soon as pressure upon the stud portion 25 is released, the back portion resumes its normal flat position through its inherent elasticity.

As shown in Figs. 1 to 8 the container is adapted to contain keys. The key-holding assembly may be of any standard type, the one illustrated consisting of a plate 28 provided at its upper edge with a curled tubular portion 29 provided with slots 30 in which are engaged the shanks of key supporting hooks 31. These hooks are provided within the tubular portion 29 with ball ends 32, which permit swiveling movement of the hooks. The plate 28 is secured to the back portion by means of studs 33 integrally formed upon the back portion 10 and engaged through holes 34 in the plates, these studs being headed over, as at 35, by applying heat and pressure to their ends. The use of thermoplastic material for the container permits this. It will be understood that the plate 28 may, if desired, be secured by rivets, eyelets, staples, or other suitable means. Upon the inner side of the cover portion 11 there is provided a transparent sheet of acetate or the like 36 adapted to form a pocket for identification cards or the like, being preferably secured by studs 37 integrally formed upon the cover portion and headed over by heat and pressure, as at 38.

The slit between the upper end walls 17 and 20 permits one or more of the keys to be disposed outside of the container, as shown in Fig. 8, by swinging the key upwardly while the container is in open position and thereupon closing the container so that the shank portion of the hook is engaged in the slit. The inherent elasticity of the material of the container permits the slit to open sufficiently for this purpose and also allows the hook to swivel,

In Fig. 13 the container is shown as adapted to contain a memorandum pad or note book 39, the back 40 of which is preferably secured to the back portion 16 of the container by studs 41 integrally formed upon the container and headed over by heat and pressure, as at 42. A pencil 43 may be conveniently carried in the container by placing it within the space formed by the connecting hinge portion 12 and the ends of the upper and lower end walls.

In Fig. 14 the container is shown as adapted for containing loose-leaf sheets 44 carried upon a separable ring unit 45, the latter being secured by rivets 46 to the inner side of the connecting portion 12.

In Fig. 15 the container is shown as adapted to contain a box of cleaning tissue or the like 47, the individual sheets 48 being drawn therefrom through the slit provided between the upper end walls 17 and 20. This cleaning tissue may be of the type where the sheets are so folded and interengaged that as one sheet is withdrawn it pulls out the end of the succeeding sheet.

In Fig. 16 the container is shown as adapted to have a coin dispenser 49 carried therein. A modified form of the container is illustrated in which the slit at the top of the container is dispensed with, the upper walls 17a and 20a being of equal height with the other walls, and the wall 17a being disposed within the wall 20a.

Fig. 17 shows the container used as a picture carrying and display case. Snapshots or the like 50 are secured within the back and cover portions, and for this purpose these portions are provided with headed over studs 51 engaged through perforations in the pictures in a similar manner to the attachment of the transparent acetate sheet 36 as shown in Fig. 1. If desired such acetate sheets may be provided as covers or pockets for the pictures. In the closed position the container provides a flat protective case for the pictures so that they may be conveniently carried in the pocket, while in the open position the container is self-supporting on a desk or the like, the hinge portion 12 maintaining the back and cover portions in open position so that the pictures are attractively framed by the upstanding wall portions. The wall portions are all of equal height as in the modification shown in Fig. 16.

What is claimed is:

1. As an article of manufacture, a one-piece moulded container formed of pliable and elastic material of the type having plastic "memory," comprising a back portion and a cover portion 55 each having inner, outer and side edges and disposed in spaced parallel and registering relation with each other in the closed position of the container, and a hinge web connection integral with and extending between said inner edges and 60 convexly curved transversely in the closed position of the container, said cover portion having an outer wall adjacent to its outer edge, said back portion having an outer wall adjacent to its outer edge disposed inwardly of said outer wall of said cover portion in the closed position of the latter, said outer walls of said back and cover portions each having a catch portion 65 extending toward the other wall and engageable and disengageable respectively through parallel outward and inward shifting movement of said back portion relatively to said cover portion, said hinge portion in the closed position of the container exerting an equalizing force to maintain said back and cover portions in register, and adapted 70

through elastic deformation to permit said back portion through inward pressure on its outer edge to be inwardly moved in parallel relation to said cover portion to disengage said catch portions and through its inherent elasticity to exert opening pressure on said cover portion, and further adapted through plastic "memory" to exert outward pressure on said back portion to engage said catch portions with each other following the closing of said cover portion.

2. As an article of manufacture, a one-piece moulded container formed of pliable and elastic plastic material of the type having plastic "memory," comprising a back portion of substantially rectangular outline, a cover portion of corresponding rectangular outline, each having inner, outer and side edges and disposed in spaced parallel and registering relation with each other in the closed position of the container, and a hinge web connection integral with and extending between said inner edges and convexly curved transversely in the closed position of the container, said cover portion having an outer wall adjacent to its outer edge, said back portion having an outer wall adjacent to its outer edge disposed inwardly of said outer wall of said cover portion in the closed position of the latter, said outer walls of said back and cover portions each having a laterally disposed catch portion extending toward the other wall and engageable and disengageable respectively through parallel outward and inward shifting movement of said back portion relatively to said cover portion and said outer walls having cooperating cam portions 30 adapted as said cover part is swung into closed position to exert inward shifting movement to said back portion to dispose said catch portions in laterally offset position, said hinge portion in the closed position of the container exerting an equalizing force to maintain said base and cover portions in register, and adapted through elastic deformation to permit said base portion through inward pressure on its outer edge to be inwardly moved in parallel relation to said cover portion to disengage said catch portions and through its inherent elasticity to exert opening pressure on said cover portion, and further adapted through plastic "memory" to exert outward pressure on said back portion to engage said catch portions with each other following the closing of said cover portion and said inward shifting thereof by said cam portions.

3. As an article of manufacture, a one-piece moulded container formed of pliable and elastic plastic material of the type having plastic "memory," comprising a back portion and a cover portion, each of substantially rectangular outline and each having inner, outer and side edges and disposed in spaced parallel and registering relation with each other in the closed position of the container, and a hinge web connection integral with and extending between said inner edges and convexly curved transversely in the closed position of the container, said cover portion having an outer wall and side walls parallel to and adjacent said outer and side edges of said cover, said outer wall and at least one of said side walls being of equal height and having their lower edges parallel to said back and cover portions and engageable by the upper side of said back portion in the closed position of the container, said back portion having an outer wall parallel to and adjacent its outer edge disposed inwardly of said outer wall of said cover portion in the closed position of the latter, said

outer walls of said back and cover portions each having a catch portion extending toward the other wall and engageable and disengageable respectively through parallel outward and inward shifting movement of said back portion relatively to said cover portion, said hinge portion in the closed position of the container exerting an equalizing force to maintain said back and cover portions in register, and being capable through elastic deformation to permit said back portion through inward pressure on its outer edge to be inwardly moved in parallel relation to said cover portion to disengage said catch portions and through its inherent elasticity to exert opening pressure on said cover portion, and further adapted through plastic "memory" to exert outward pressure on said back portion to engage said catch portions with each other following the closing of said cover portion.
